UNITED STATES PATENT OFFICE

GEORGE F. McDougall, of Portland, Oregon, assignor, by direct and mesne assignments, to Oregon Textile Machines, Inc., a corporation of Oregon

FRINGE MAKING MACHINE

Application filed November 4, 1929. Serial No. 404,598.

My invention relates to the textile art and that portion of it having to do with automobile robes, steamer rugs and other pieces of woolen materials having fringes at the ends thereof.

Heretofore so far as this inventor is able to learn these fringes have been made in the following manner, to-wit: The articles requiring fringes come from the looms having a considerable number of the robes or other articles woven continuously in one piece, except that where it is desired to subsequently divide the articles the shuttles are stopped and no longer throw any woof or cross threads and a varying amount of warp threads are run through sufficient to make two fringes, usually about eight inches for a fringe that will be slightly under four inches long on completion.

In the present state of the art the fringes are made manually one at a time and the improvement consists in supplying a machine that makes all of them at once across the width of the robe in a very small fraction of the time required for hand work, and the substitution of machine accuracy for the human equation.

It will be understood that the fringes are twisted and tied prior to a shrinking operation or treatment after which the twist remains in the fringes and the tie thread is cut out.

The drawings in nine views showing the machine in partial assembly, details of different parts and a figure illustrating the work which the machine accomplishes, accompany and are made a part of these specifications with reference letters on the drawings to tie them into the text. The drawings are partly diagrammatic as will be hereinafter pointed out and one of them, Fig. VII, is drawn to a larger scale than the other views for the purpose of more clearly showing the construction; however, dimensions are not a material feature of this invention.

Fig. I is a side elevation partly sectioned of the machine; Fig. II is a sectional view of Fig. I on the line II-II, Fig. I, with some non-essential parts omitted; Fig. III is a view of a robe used to illustrate the purpose of

the machine; Fig. IV is an enlarged view of a single twister element of which a considerable number appear in the machine; and Fig. V is an orthographic projection of Fig. IV to more clearly illustrate its character. 55 Fig. VI is a plan view of a part of the machine taken on the line VI-VI of Fig. II and Fig. VII is an enlarged view of a portion of Fig. II drawn to an increased scale to more clearly indicate the relation of the parts. 60 Fig. VIII is a view of the needle bracket hereinafter described in detail and containing a needle, also the subject of further description, and illustrates in a diagrammatic way means for keeping the needle in alignment 65 with the parts with which it co-operates; Fig. IX is a section on the line IX-IX at Fig. VIII and illustrates the means for needle support.

In order to understand the operation and 70 follow the construction of this machine, I will first describe its function. Referring to Fig. III, numeral 1 represents a view of a robe as it comes from the loom with a portion of the woof threads, 2, omitted. And the 75 warp threads, 1, have no cross threads for a distance of several inches, usually about eight inches, when the woof threads, 2, are started again and the weaving progresses for the length of a robe, when another such omission 80 takes place defining the length of a completed robe including the fringes. To make the fringes, an approximately equal number of the warp threads, 1, are gathered into a bundle and given a desired number of turns 85 or twists, which is clearly shown in Fig. VI, reference numeral 1B, where it will also be observed that the selected bundle of warp threads being twisted at the center, the twist will be in opposite directions on each side 90 of the center.

A roll of robes having the unwoven portions indicated at numeral 1 in Fig. III is passed between the receiving rollers 3 and 3a which are diagrammatically shown in Fig. I 95 as supported by the stands, 3b, the center line of the robes being indicated by the broken line, 4, and passed through the machine and thence between rollers 5 and 5a diagrammatically shown in Fig. I as supported by the 100

stand 5b. Means for the proper operation of these rollers will be provided but are not shown in the drawings. When a portion of the robe as illustrated by numeral 1 is centrally over the point marked 1A in Fig. I, the gathering comb, 6, is depressed by a preferred means diagrammatically illustrated as the lever, 7, having a fulcrum and a connection with the gathering comb at 9, when the teeth 10 of the gathering comb, 6a, will divide the warp threads, 1, into approximately even divisions or bundles as shown at 1a in Fig. III and these bundles will be crowded up into the throat of the teeth, 6a, the precise point being indicated by numeral 6b in Fig. II and the robe being under some tension between the rollers 3 and 3a and 5 and 5a, this gathering of the warp threads will be substantially completed before any considerable depression of the center line of the robe as indicated by numeral 4 takes place. A continued depression of the gathering comb, 6, will spring the gathered strands and the robe in a downward direction toward the receiving comb, 10, the teeth of which, it will be noted, form a shield, support and bearings for a twister element indicated as a whole by the numeral 11, the twisting pin of which, 11e, points toward the descending gathered strands.

The twister-element, 11, shown in two views as Fig. IV and Fig. V, is a quill, the hubs of which are journals and it has a gear, 11b, between the hubs. The particular feature of 35 the twister-element is the slot, 11d, which intercepts both the body of the quill and the gear for the full length of the element and comprises a pocket or receptacle for sidewise entry of a gathered bundle of threads to be 40 twisted into a fringe. It contains a positive means for engaging the bundle of threads, in this case the twisting pin, 11c, which is a pointed pin projecting across the axis of the quill toward the open side of the slot 11d, 45 within the slot 11d, but not beyond the bounding circumference line of the hubs. The circular pitch of the gear, 11b, should be such that only one tooth thereof will be cut out in forming the slot and that without cutting 50 away any of the roots of the next adjoining teeth. This element can be made with only one journal and with the gear at one end of the quill if desired; though it is inferior.

The function of the twister-element is to 55 receive the bundle of threads by sidewise entry, both ends of the threads being held in the weave, permit them to be engaged by the engaging device and twisted as the twister-element is revolved by appropriate means. 60 It will be essential that all the twister-elements employed shall be timed so that they may be stopped with their respective slots in registration with the spaces between the teeth of the receiving comb 10, in order to 65 smoothly accept the bundle of threads to be

twisted and they must likewise register on the completion of the twist that the twisted bundles may be discharged after a twist holding thread has been passed through them.

Therefore, I have used the timing gear 75 shown which provides that all the gears will be in mesh with a driving means at all times despite the fact that a tooth is removed from each gear, 11b.

As the gathered strands are forced between 75 the points of the receiving comb, 10, into the twister-element 11, they are penetrated at their approximate center by the twisting pin, 11c. Disposed between the gathering comb, 6, and the receiving comb, 10, is the die-block, 12, and 12a, made in two pieces and having transverse grooves, 12c, and a longitudinal groove, 12d, the grooves in 12 and 12a being designed to register when they are brought together by the depression of the gathering 20 comb, 6, to which 12 is securely attached so that when they are thus brought together as shown in Fig. I the respective longitudinal grooves, 12c and 12d, become round holes: the grooves 12c when thus brought together 25 will form a hole having a slightly larger radius than the throat, 6b, in the gathering comb, 6, and the throat of the twister element, 11, in order that the gathered strands shown at 1B may twist therein freely and substantially without friction.

It is now desired that the twister-element, 11, be given a desired number of complete revolutions depending upon the degree of twist required in the completed fringes. The slotted gear, 11b, of each twister-element, 11, is meshed with an adjacent twister-element on both sides except of course the one at each end of the assembly; and it is obvious that in making even a partial revolution the slots will come together and they will no longer turn; this difficulty is overcome by taking the drive from the pinions, 15, which are shown with their axes at an angle from the vertical center line of the twister-elements 11, and they are so disposed that having two adjacent twister-elements, 11, supplied with driving pinions, 15, at equal and opposite angles from their vertical center lines, one twister-element may be omitted from having a separate drive and be driven by adjacent twister-elements. These pinions, 15, are mounted on shafts, 16, provided with bearings at 17 and another bearing that is not shown and are each given appropriate motion by the beveled gear pairs, 18, one element of which is mounted upon the shaft, 19, upon which also is mounted the pinion, 20, co-operating with sector gear, 21. Sector gear, 21, is attached to the lever, 22, which has a fulcrum at 23 and it is obvious that moving the lever, 22, in a direction indicated by the arrow, 24, will cause a revolving motion through the gear train and shafts to be imparted to the twister-elements, 11, and that they will twist the im- 110 115 120 125 130

paled strands in the manner indicated at 1B, Fig. VI.

The twist having been completed by an exactly even number of turns of the twister-element, 11, the twisting pin, 11c, will point in the same direction as before the twist started. The needle, 25, which is preferably made with a separate point, 26, having a springeye at the point, 26b, is supported by 10 the bracket, 27, and movable transversely of the machine through the longitudinal groove, 12d, now become a round hole by bringing together of the two halves of the die-block, 12 and 12a; and as the needle is moved through 15 the said groove, 12d, it will intercept and pass through a twisted strand at each of the transverse grooves, 12c.

Having passed through all of the twisted strands between two robes as indicated at H 20 in Fig. III, the bight of a yarn, 28, or suitable thread will be snapped into the eye of the needle, 26b, and the needle will be withdrawn to its original position and thus pull a double strand of the yarn, 28, through the twisted 25 strands 1B, the yarn, 28, will be cut from the needle eye, 26b, manually and the twisting and tying operation being completed, the lever, 7, will be allowed to resume its original position under the influence of the 30 springs, 30 and 31, the strands, 1B, being twisted in opposite directions from the center will be prevented from untwisting by the inserted yarn, 28; the rollers, 3 and 3a, 5 and 5a, will then be caused to function by appropriate 35 means; the cycle of operations previously described repeated at the next adjacent space where it is desired to construct a fringe between two robes.

A lifting bar, 32, is provided attached to 40 the gathering comb, 6, to lift the twisted strands out of the receiving comb, 10, should they show any tendency to stick.

Numerous mechanical parts which in the drawings bear no reference numerals and are 45 not mentioned in the specification will be noted. And the reason for their omission is that their purpose is so obvious that anyone capable of understanding the drawings and specification can perceive it instantly and in 50 the interest of clarity of the drawings and to eliminate surplusage in the written specification they are not mentioned.

I do not bind myself exactly to the construction shown and reserve the right to vary 55 details of construction, for example the machine is shown to be horizontal when this is not necessary for its successful operation and the drawings therefor are intended to show 60 the operable relation of my new elements to other elements whether new or old for the new result as described and specified.

Having thus fully described and illustrated my invention, so that a competent designer could construct and direct the opera- 65

tion of one, what I claim as new and desire to secure by Letters Patent, is:

1. In a fringe making machine, a gathering comb of the character described, adapted to gather and divide warp threads into bundles to be twisted with a twister-element in position to receive each bundle of threads. 70

2. In a fringe making machine, a receiving comb of the character described, adapted to receive segregated bundles of threads from a gathering device with a twister-element in the throat of each receiving comb tooth. 75

3. In a fringe making machine, a die-block of the character described having transverse slots for strands to be twisted and a needle slot at right angles thereto in combination with a plurality of twister-elements. 80

4. In a fringe making machine, a two piece die-block having parallel passageways to hold strands to be twisted and a transverse needle-way intercepting each transverse passage and a co-operating needle whose function is to pass a thread through twisted strands and having a twister-element in end-wise registration with each parallel strand 90 passageway. 95

5. In a fringe making machine, the combination of a gathering comb and a receiving comb to divide warp threads into approximately even bundles in combination with twister elements adapted to receive said bundles. 100

6. In a fringe making machine, the combination of a gathering comb, a receiving comb of the character described, and a plurality of gear driven twister elements to twist each strand uniformly. 105

7. In a fringe making machine, the combination of a plurality of twister-elements having twisting pins of the character described and slotted gears partially surrounding said twister-elements and a timing gear drive for said twister-elements to produce a constant in-mesh condition for each twister element. 110

8. In a fringe making machine, the combination of a gathering means, a receiving means and twister-elements of the character described, for gathering warp threads into approximately equal bundles, and a gear drive for said twister-elements to cause them to execute synchronously a desired number of complete revolutions. 115

9. In a fringe making machine, the combination of a gathering comb and a receiving comb adapted to gather warp threads into approximately equal bundles and deliver them to twister elements, a plurality of twister-elements to receive said bundles, means for operating said twister-elements to twist said bundles, means comprising a die-block of the character described to hold the said twisted bundles in alignment and a needle adapted to pass a restraining thread 120 125 130

through said twisted bundles to prevent their untwisting.

10. In a fringe making machine, gathering comb means of the character described, receiving comb means having twister-elements in position in the throat of each space between teeth adapted to receive strands gathered by the first named means and die-block means adjacent the first two named means for holding gathered strands in the same plane for the purpose specified.

11. In a fringe making machine, a gathering means, a receiving means for strands to be twisted and a plurality of twisting elements in the same plane consisting of slotted quill members having bearings and driving means, the slots of said quill members having twisting pins projecting across the axes of said quill members and adapted to engage contained strands.

12. In a fringe making machine, a gathering means, a receiving means for strands to be twisted and a plurality of twister-elements within said receiving means, bearings for said twister-elements, driving means for said twister-elements and means incorporated with said twister-elements for positively engaging contained strands to impart to the said strands the movement of the twister-elements.

13. In a fringe making machine, a strand gathering means, a co-operating strand receiving means, twister-elements incorporated with the last named means and means for holding twisted strands in alignment, with guideways for strand penetrating means for inserting a twist restraining yarn.

14. In a fringe making machine, the combination of gathering means, twister-elements, operating mechanism for said twister-elements, die-block means for aligning the twisted produce and needle means for penetrating twisted strands of said product.

GEORGE F. McDougall.
